(57) **CLAIM**

The ornamental design for a connector module, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-top-right perspective view of a connector module showing a first embodiment of my new design, wherein the color portion forms a part of the claimed design;

FIG. 2 is a rear-top-right view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and

FIG. 8 is a left side view thereof;

FIG. 9 is a front-top-right perspective view of a connector module showing a second embodiment of my new design, wherein the surface shading portion indicates color contrast;

FIG. 10 is a rear-top-right view thereof;

FIG. 11 is a top view thereof;

FIG. 12 is a bottom view thereof;

FIG. 13 is a front view thereof;

FIG. 14 is a rear view thereof;

FIG. 15 is a right side view thereof; and

FIG. 16 is a left side view thereof; and

FIG. 17 is a front-top-right perspective view of a connector module showing a third embodiment of my new design;

FIG. 18 is a rear-top-right view thereof;

FIG. 19 is a top view thereof;

FIG. 20 is a bottom view thereof;

FIG. 21 is a front view thereof;

FIG. 22 is a rear view thereof;

FIG. 23 is a right side view thereof; and

FIG. 24 is a left side view thereof.

The broken lines in the drawings illustrate portions of the connector module that form no part of the claimed design.
